ALARM CLOCK

Waldemar Blessing, Waldkirch im Breisgau, Germany,
assignor to Blessing-Werke KG, Waldkirch im Breisgau,
Germany

Filed Sept. 20, 1971, Ser. No. 182,289

Claims priority, application Germany Mar. 20, 1971

Term of patent 14 years

Int. Cl. D10—01

U.S. Cl. D42—7 R

FIG. 1

FIG. 2

FIG. 3

FIG. 1 is a front perspective view of an alarm clock showing my new design;

FIG. 2 is a right side elevational view thereof, the left side being a mirror image thereof;

FIG. 3 is a rear perspective view thereof.

The side of the alarm clock not shown in FIG. 2 has an appearance identical with the appearance of the side shown in FIG. 2.

I claim:

The ornamental design for an alarm clock, substantially as shown and described.
